UNITED STATES PATENT OFFICE

154,187

DESIGN FOR A REFRIGERATOR

Ray C. Sandin, Oak Park, Ill., assignor to Hot-point Inc., a corporation of New York

Application February 25, 1948, Serial No. 144,733

Term of patent 14 years

(Cl. D67—3)

To all whom it may concern:

Be it known that I, Ray C. Sandin, a citizen of the United States, residing at Oak Park, in the county of Cook, and State of Illinois, have invented a new, original, and ornamental Design for a Refrigerator, of which the following is a specification, reference being had to the accompanying drawing, forming a part thereof.

In the drawing, Figure 1 is a front elevational view of a refrigerator embodying my new design;

Fig. 2 is a left-hand side elevational view thereof, the right-hand side elevational view thereof, not shown, being substantially plain; and Fig. 3 is a top plan view thereof.

I claim:

The ornamental design for a refrigerator, as shown and described.

RAY C. SANDIN.
